ELECTRIC SELECTIVE SIGNALING SYSTEM

Leslie Richard Frost, Southampton, England

Application January 8, 1947, Serial No. 720,841
In Great Britain June 6, 1944

5 Claims. (Cl. 177—353)

1

This invention has for its object to provide an improved form of sender and receiver for an electric selective signalling system of the kind in which manual setting of a control element of the sender to one of a series of alternative positions effects movement to a corresponding position of a follower element of the receiver, so that the position of the follower element will always conform with that of the control element.

The sender and receiver according to the invention are reversible in two senses. Firstly they are reversible as regards function, i. e. they can be used at will either to send or to receive signals, the same element of the device functioning as control element or as follower element according as to whether signals are being transmitted or received. Secondly they are reversible as regards direction of movement, i. e. the control element of the sender can be given either a forward movement or a reverse movement which will be faithfully copied by the follower element of the receiver.

The invention provides a mechanism, which is operable at will to function either as a sender or as a receiver for an electric selective signalling system of the above kind, and which comprises a differential gear, having two coaxial sun wheels and a planet wheel meshing with both of said sun wheels and mounted for bodily rotation about the common axis of said sun wheels, the planet wheel being coupled to the control element so as to be moved forwardly or in a reverse direction in relation to the sun wheels according to the movement of the control element, a set of keys or equivalent manipulative members operatively connected to the control element, each key serving, when operated, to move the control element to a definite position allotted to that key, means associated with the sun wheels for constraining them, on movement of the planet wheel as aforesaid, to execute a relative rotation which is determined in direction and extent by the direction and extent of said movement of the planet wheel, and a two-way electrical unit which is effective on the one hand, in response to actuation of the setting means aforesaid, to produce a variable signal for actuating a distant receiver which is representative of the direction and extent of said relative rotation of the sun wheels, and on the other hand to produce, in response to a signal received from a distant sender, relative rotation of said sun wheels, which is determined as regards both direction and extent by said signal.

The movement imparted to the planet wheel by operation of the setting means may be either a rotational movement about its axis, or a bodily

2

movement of rotation about the common axis. The sun wheels are preferably normally stationary, and if so the sun wheels are constrained to execute the above-mentioned relative movement by associating with them restraining devices, e. g. of the pawl and ratchet type, arranged in the former case to permit only of movement of the sun wheels in the same direction and, in the latter case, to permit only of movement of the sun wheels in opposite directions.

I do not, however, exclude the possibility of employing constantly rotating sun wheels. The sun wheels must then be driven in the same direction when operation of the setting means effects rotation of the planet wheel about its axis, and in opposite directions when operation of the setting means effects bodily rotation of the planet wheel about the common axis of the sun wheels. Where the sun wheels are driven, the drive acts, as described later, as the constraining means for producing the required relative rotation of the sun wheels.

In the case of a mechanism having normally stationary sun wheels, the two-way electrical unit may be constituted by a make and break device and a solenoid and plunger associated with each sun wheel, the make and break devices operating alternatively, when the mechanism is in use as a sender and according to the direction of relative rotation of the sun wheels, to transmit a signal by making or breaking a circuit, said signal consisting of a series of impulses determined in number by the extent of relative rotation of the sun wheels, and the solenoids and plungers operating alternatively, when the mechanism is in use as a receiver and according to the direction of relative rotation of the sun wheels of the distant sender, to effect relative rotation of the associated sun wheels to an extent determined by the number of impulses in the signal received from the distant sender. This method is convenient because it permits of transmission of signals by means of electro-magnetic radiation using alternative radio frequency channels or, as later described, by means of a single line using an earth return. While it will ensure that the receiver will remain in step with the sender so long as the connecting link is effectively in operation, it does not, however, provide for positive return into step of the receiver when the link is re-established after a fault has developed and one or more signals may have failed to reach the receiver.

As an alternative therefore, the sender and receiver may be connected by a circuit which

includes a pair of resistances or the like, one associated with the sender and the other with the receiver, the circuit being arranged to develop an out-of-balance current when they are out of balance, the two-way electrical unit associated with each mechanism comprising means operating, when the mechanism is acting as a sender, to vary the associated resistance by an amount representative of the direction and extent of movement of the sun wheels of said mechanism, and means operating, when the mechanism is acting as a receiver and in response to the out-of-balance current in the circuit, to effect relative rotation of the sun wheels of the mechanism to restore the balance of said resistances.

With this arrangement, even if a fault has developed, the receiver must of necessity come into step, by rebalancing the resistances, when the fault is put right. Where resistances are employed as the balancing elements direct or alternating current may be used in the circuit. Where alternating current is used or the connection between sender and receiver is by electromagnetic radiation, capacities or inductances can be used as the balancing elements, the local circuits associated with the sender and receiver reacting so that transmission ceases when the elements are balanced.

Some practical embodiments of the invention will now be described in detail by way of example, with reference to the accompanying drawings, in which:

Fig. 1 is a side elevation of a differential gear unit for use in a sender or receiver according to the invention,

Fig. 2 is a section on the line II—II in Fig. 1,

Fig. 3 is a diagrammatic perspective view of a sender or receiver employing the differential gear unit of Fig. 1,

Fig. 4 is a circuit diagram to illustrate the use of mechanism as shown in Fig. 3,

Fig. 5 is a diagrammatic perspective view showing an alternative form of sender or receiver, and

Fig. 6 is a circuit diagram to illustrate the use of mechanism as shown in Fig. 5.

Like references indicate like parts throughout the figures. In Figs. 4 and 6 parts associated with the receiver are differentiated from the same parts of the sender by the addition of the letter *a* to the reference characters.

Referring first of all to Figs. 1 and 2, the differential gear unit comprises a pair of coaxial sun wheels 10, 11 rotatably mounted on a shaft 12 journaled in a supporting framework 13. To the sun wheel 10 is fixed a ratchet wheel 14 and to the sun wheel 11 is fixed a ratchet wheel 15. A pawl 16 permits the ratchet wheel 14 and associated sun wheel to rotate only in the clockwise direction as seen in Fig. 2, and a pawl 17 permits the ratchet wheel 15 and associated sun wheel to rotate in the anti-clockwise direction only as seen in Fig. 2. Meshing with the two sun wheels is a planet wheel 18, which is freely rotatable on a stud 19 projecting from a boss 20 pinned to the shaft 12 by a screw 21.

Referring now to Fig. 3, the shaft 12 in this case constitutes the control element, when the mechanism is used as a sender, which serves to effect variable but controlled relative rotation of the sun wheels under the control of a set of manually operable keys 22. When the mechanism is used as a receiver the shaft 12 will act as a follower element, to take up a position corresponding to that of the shaft of the sender, this move-

ment being derived from relative rotation of the sun wheels of the receiver under the control of the electrical signal as later described. The shaft 12 of the receiver will be utilised for setting any desired mechanism, e. g. the type wheel of a tele-printer, into a position corresponding to and determined by the setting of the keys of the sender.

As shown in Fig. 3, the shaft 12 carries a flat plate 23 and the keys 22 have at their lower ends plates 24 mounted at different angles to the stem of the key. When any given key is depressed, its plate 24 will press on the plate 23 and so rotate the plate 23 and shaft 12 until the two plates are parallel. The extent and direction of the rotation of the shaft 12 will thus depend upon which of the keys has been depressed.

Rotation of the shaft 12 causes bodily rotation of the planet wheel 18 about the common axis of the sun wheels. If the shaft 12 rotates clockwise as seen from the right in Fig. 3, the sun wheel 10 will be prevented from following owing to the pawl 16 associated with its ratchet wheel 14 and the planet wheel will roll on the stationary sun wheel 10 rotating the sun wheel 11 and ratchet 15 clockwise. At each step of clockwise rotation of the sun wheel 11 and ratchet 15, the pawl 17 will be clicked up by the ratchet teeth to make contact with a spring contact 26. A series of impulses will thus be caused in a circuit associated with contact 26, the number of impulses being determined by the extent of rotation of the shaft 12.

Similarly anti-clockwise rotation of shaft 12 as seen from the right in Fig. 3, will result in the sun wheel 11 remaining stationary and the sun wheel 10 turning anti-clockwise and imparting through the pawl 16 and cooperating contact 25 the appropriate number of impulses to the circuit including contact 25.

Associated with the ratchets 14, 15 are solenoids 27, 28 respectively. Each solenoid surrounds a plunger 29, carrying a spring pawl 30 engaging the teeth of the associated ratchet, and normally held extended by a spring 31. Each time one of the solenoids receives an impulse from a distant sender, its plunger is retracted to move the associated ratchet by one step.

As shown in Fig. 4, parallel circuits are taken from earth, through reversed batteries 32, normally open contacts 25, 26 and a rectifier 33 to the single line 34 leading from the sender to the receiver. The solenoids 27, 28 are connected in parallel between earth and the rectifier 33.

An earthing switch 84 is associated with the reversed batteries 32 and earthing switches 35 are associated with the solenoids. When the mechanism is to be used as a sender, switch 84 is closed and switches 35 are open (see the left hand side of Fig. 4). When it is to be used as a receiver, switch 84 is open and switches 35 are closed (see the right hand side of Fig. 4).

As already explained, the direction of rotation of the shaft 12 determines whether contacts 25 or 26 are closed and the extent of rotation of shaft 12 determines the number of impulses transmitted. When contacts 25 are closed, say three times, by rotation of sun wheel 10 through three steps, current is passed through the rectifiers to solenoid 27^a associated with sun wheel 10^a of the receiver. This causes sun wheel 10^a to move three steps and rotate the follower shaft of the receiver by an equal amount and in the same direction as the control shaft of the sender. The same result takes place, of course, when the direction of rotation of the control shaft is such as

to operate contacts 26, the sun wheel 11^a of the receiver then moving to effect the required slave movement of the follower shaft of the receiver.

The armatures could of course be arranged to control escapement mechanisms associated with the sun wheels instead of effecting positive operation thereof as illustrated.

In the embodiment of Fig. 5, the pawls 16, 17 are arranged to prevent movement of the normally stationary sun wheels 10, 11 in the same direction. In this case the control movement is imparted to the differential unit, under the control of keys 22, by causing the planet wheel 18 to rotate about its axis. To this end the planet wheel carries a pinion 55 engaging a rack 36 formed on a part 38 which is rotatable about and movable along the axis of shaft 12 within the confines of a control bar 37. The control bar 37 thus partakes of the sliding movement of the part 38 in relation to the shaft 12. The control bar 37 is formed with a V-depression 39 for engagement of the keys, so that the longitudinal position of the control bar in relation to the shaft 12, and consequently the direction and extent of the rotation of the planet wheel 18 about its axis, are determined by the selected key. It will be understood that according to the direction of movement of the control bar, one or other of the sun wheels will be held stationary by its pawl, and the other will rotate.

The effective controlling element of the sender and corresponding follower element of the receiver is, in this case, constituted by the bar 37 which carries a contact 40 cooperating with a resistance 41.

As shown in the circuit diagram in Fig. 6, the resistances 41, 41^a of the sender and receiver are cross connected, and the contacts 40, 40^a are normally in a position such that the resistances are in balance, i. e. $R+r_1=R_1+r$ so that equal currents flow through the upper and lower limbs of the two-pole relays 42, 42^a. When however the control bar 37 of the sender takes up a new position, the resistances are thrown out of balance, and the current through the upper coils of relays 42, 42^a becomes greater or less than that flowing through the lower coils. The pivoted armatures 43, 43^a of the relays therefore move to connect in circuit lines 44, 44^a or lines 45, 45^a. These, when connected in circuit energize electric motors for rotating the sun wheels of the associated mechanisms, the direction of relative rotation being determined by which pair of lines is in circuit. Movement thus imparted to the receiver continues until its contact 40^a has moved, as above described with reference to Fig. 5, to rebalance the resistances.

Switches 46, 46^a are in the position shown when the left hand unit is acting as the sender, and lines 44, 45 will be earthed when connected in circuit and will not therefore actuate their associated electromagnetic devices. When the right hand unit is to act as sender, the switches 46, 46^a are reversed, and lines 44, 45 will be operative, when placed in circuit, to actuate their electromagnetic devices, lines 44^a, 45^a being then earthed.

I am aware that an electric signalling system has been proposed having a sender (which can also operate as a receiver) comprising a handle which is movable in either direction from a neutral position to establish one of two alternative circuits. The circuit so established operates through an electromagnet, to free one of the two sun wheels of a differential gear for movement

under the influence of an escapement. This sun wheel drives the planet wheel, and a member connected thereto in time breaks the circuit again, the movement permitted to the sun wheel being proportional to the movement of the handle. As the sun wheel rotates electric signals are emitted to cause the corresponding sun wheel of the receiver to execute a corresponding movement. When the apparatus is acting as a receiver, one of two electromagnets is energized by the sender to permit the corresponding sun wheel to move under the action of the escapement. This mechanism differs from that according to the invention in that no movement is communicated to the planet wheel by the setting movement of the handle, which serves only to free one of the sun wheels for escapement movement. Nor is a set of keys or the equivalent provided, by the selection of any of one of which a desired corresponding movement may be imparted to the receiver.

What I claim as my invention and desire to secure by Letters Patent is:

1. A mechanism, operable at will to function either as a sender or as a receiver for an electric selective signalling system of the kind specified, and comprising a differential gear, having two coaxial sun wheels and a planet wheel meshing with both of said sun wheels and mounted for bodily rotation about the common axis of the sun wheels, the planet wheel being coupled to the control element so as to be moved forwardly or in a reverse direction in relation to the sun wheels according to the movement of the control element, a set of keys or equivalent manipulative members operatively connected to the control element, each key serving, when operated, to move the control element to a definite position allotted to that key, means associated with the sun wheels for constraining them, on movement of the planet wheel as aforesaid, to execute a relative rotation which is determined in direction and extent by the direction and extent of said movement of the planet wheel, and a two-way electrical unit which is effective on the one hand, in response to actuation of the setting means aforesaid, to produce a variable signal for actuating the distant receiver which is representative of the direction and extent of said relative rotation of the sun wheels, and on the other hand to produce, in response to a signal received from a distant sender, relative rotation of said sun wheels which is determined as regards both direction and extent by said signal.

2. A mechanism as claimed in claim 1, in which the sun wheels are normally stationary, in which operation of the setting means effects rotational movement of the planet wheel about its axis, and in which the constraining means restrain the sun wheels against rotation in the same direction.

3. A mechanism as claimed in claim 1, in which the sun wheels are normally stationary, in which operation of the setting means effects bodily rotation of the planet wheel about the common axis of the sun wheels, and in which the constraining means restrain the sun wheels against rotation in opposite directions.

4. A mechanism as claimed in claim 1, wherein the sun wheels are normally stationary, operation of the setting means effecting bodily rotation of the planet wheel about the common axis of the sun wheels and the constraining means restraining the sun wheels against rotation in opposite directions, and wherein the two-way electrical unit comprises a make and break device and a

solenoid and plunger associated with each sun wheel, the make and break devices operating alternatively, when the mechanism is in use as a sender and according to the direction of relative rotation of the sun wheels, to transmit a signal by making or breaking a circuit, said signal consisting of a series of impulses determined in number by the extent of relative rotation of the sun wheels, and the solenoids and plungers operating alternatively, when the mechanism is in use as a receiver and according to the direction of relative rotation of the sun wheels of the distant sender, to effect relative rotation of the associated sun wheels to an extent determined by the number of impulses in the signal received from the distant sender.

5. The combination of a pair of mechanisms as claimed in claim 1, in which the sun wheels are normally stationary, operation of the setting means effecting rotational movement of the planet wheel about its axis and the constraining means restraining the sun wheels against rota-

tion in the same direction, one of said mechanisms constituting a sender and the other constituting a receiver, of a circuit connecting said mechanisms which includes a pair of resistances, one associated with the sender and the other with the receiver, the circuit being arranged to develop an out-of-balance current when they are out of balance, the two-way electrical unit associated with each mechanism comprising means operating, when the mechanism is acting as a sender, to vary the associated resistance by an amount representative of the direction and extent of movement of the sun wheels of said mechanism, and means operating, when the mechanism is acting as a receiver and in response to the out-of-balance current in the circuit, to effect relative rotation of the sun wheels of the mechanism to restore the balance of said resistances.
